WILLIAM MALLINSON, OF HALIFAX, ENGLAND, ASSIGNOR TO JOSEPH WILD
& CO., OF NEW YORK, N. Y.

DESIGN FOR A CARPET-PATTERN.

Specification forming part of Design No. 6,003, dated July 23, 1872.

To all whom it may concern:

Specification describing a new and original Design for a Carpet, invented by WILLIAM MALLINSON, of Halifax, in the county of York, England.

The accompanying photographic illustration fully represents my new design.

This invention relates to a new carpet-design in which two main or prominent figures are employed. One of these is of rectangular form, beveled at the corners, and with V-shaped projections in the middle of its sides. It is ornamented internally by an oval figure composed of small quatre-foils, and embracing a larger quatre-foil, and embraced by decorative scrolls. A wreath of four-leaved flowers is ar-

ranged between the oval and the border of the rectangle. This border is ornamented by small hectagons. Tufts of flowers project outwardly from the border of the rectangle. The other smaller figure is of octagonal form, and contains an ornamental scroll in the center, besides being ornamented in and about the border, in the manner clearly shown in the photograph. Wreaths of flowers and foliage are arranged between the above-mentioned principal figures.

I claim as my invention—

The design for a carpet, as shown.

WILLIAM MALLINSON.
